UNITED STATES PATENT OFFICE.

HERMAN R. ISLER, OF NORWOOD, OHIO, ASSIGNOR TO THE OAKLEY MACHINE TOOL COMPANY, OF CINCINNATI, OHIO, A CORPORATION OF OHIO.

CUTTER-SETTING INDICATOR.

1,249,629.

Specification of Letters Patent. Patented Dec. 11, 1917.

Application filed August 30, 1916, Serial No. 117,763. Renewed May 10, 1917. Serial No. 167,805.

To all whom it may concern:

Be it known that I, HERMAN R. ISLER, a citizen of the United States, and a resident of Norwood, in the county of Hamilton and State of Ohio, have invented certain new and useful Improvements in Cutter-Setting Indicators, of which the following is a full, clear, and exact description, reference being had to the accompanying drawings, forming a part of this specification.

My invention relates to means for positioning a toothed cutter so that the teeth are in such angular relation to the grinding wheel that they may be properly sharpened with any predetermined amount of clearance.

It has heretofore been the custom of skillful operators to follow clearance tables to effect the adjustment of a toothed cutter so that the teeth thereof will be in proper angular relation to the grinding wheel to give to the sharpened teeth the proper clearance angle. I am aware also that cutter setting indicators have heretofore been used wherein scale graduations and indicators have been provided between the head-stock of a grinder and a positioning pulley, whereby suitable adjustments of the nature above mentioned have been effected. In the adjustment of work on machines equipped with such indicators, however, it is first necessary to bring into registration the indicator and zero mark of the scale graduations and to lock the pulley in such position, after which the cutter to be sharpened must be secured to the pulley in the precise position with reference to the grinding wheel which it is to occupy before adjustment through the desired clearance angle. It is one of the objects of my invention to provide a cutter setting indicator wherein the work may be mounted on the pulley and then rotated to the required position with reference to the grinding wheel, after which the indicator and zero marks may be brought into registration without disturbing the position of the work. Other objects will appear from the following description of my invention.

In the drawings: Figure 1 is a plan of the head-stock of a grinder equipped with my new cutter setting indicator.

Fig. 2 is a side elevation of said head-stock.

Fig. 3 is a central section of a portion

of the head-stock and spindle illustrating my invention.

Fig. 4 is an elevation of a grinding machine showing the relation of the head-stock 60 to the other mechanism.

The numeral 1 indicates the base of the head-stock of a grinding machine. Pivotally supported on the base 1 is an angle block 2, to one face of which the head 3 65 is pivotally secured. Journaled in the head 3 is a spindle 4. Rotatably mounted on the spindle 4 is a pulley 5; a set screw 6 is provided whereby said pulley may be fixedly secured to the spindle if desired. The parts 70 thus far described are of a form and construction familiar to those skilled in the art. Secured to the spindle 4, near the end thereof, is a collar 7, a flange 8 of which is arranged to fit into an annular groove in the 75 face of the pulley 5. The rear face of the pulley 5 is provided with a flange 9.

The head 3 has a reduced end 10, providing a seat for a ring 11 which is arranged to be secured thereto by means of a thumb screw 12. The periphery of the ring 11 as will be seen, is adjacent and flush with the flange 9 of the pulley 5. Either on the ring 11 or the flange 9 are scale graduations 13, the same being shown in the present embodiment of the invention on the periphery of the ring 11. On the flange 9, or on the ring 11, if the scale graduations be placed upon said flange, is a plurality of indicator marks 14, the same being sufficient in number so 90 that one of said marks may be conveniently read from any position which the operator may be called upon to occupy during the performance of his work.

In Fig. 4 of the drawings, I have shown 95 the head-stock constructed in accordance with the foregoing description in its relationship to the other portions of a grinding machine. This machine comprises briefly a column 15 upon the upper end of which is a 100 grinder head 16. Mounted upon said column 15 is a table 17, the said table carrying the head-stock heretofore described, and the usual tail-stock (not shown). The table 17 is adjustable in the usual manner so that 105 work mounted between the head and tail-stock, or upon the head-stock alone, may be brought into any desired relationship to the emery wheel 18, on the grinder head 16. A tooth rest 19 of ordinary construction is provided.

The operation of my cutter setting indica-

tor effected by the reciprocal adjustments between the scale graduations and indicator marks will be apparent to those skilled in the art, from the foregoing description. A toothed cutter to be ground is properly centered and secured to the pulley 5 in the usual manner by means of dogs or a suitable chuck, the cutting edge of one of the teeth and the centers of the spindle 3^a and the emery wheel 18 being brought into alinement. The operator next turns the ring 11, after loosening the thumb screw 12, until the zero point of the scale registers with one of the indicators 14 on the flange 9 of the pulley, having reference in such operation to the position from which he may most conveniently read the scale; in this position the ring is locked to the head by the thumb screw 12. The pulley 5 is then rotated so that the indicator 14 registers with the mark on the scale, indicative of the degree of clearance to be given the sharpened tooth. The head-stock is next moved in the ordinary manner so that the cutting edge of the tooth is horizontally at right angles to the grinding surface of the emery wheel at the point of contact. Subsequent teeth are readily brought into proper position for grinding by bringing each tooth in succession to position on the rest 19.

30 What I claim as new and desire to secure by Letters Patent is:

31 1. In a device of the character described, 32 the combination with a head-stock and a cutter supporting member rotatably mounted 33 therein, of an indicating member adjustably 34 mounted on said head-stock adjacent said

35 cutter supporting member, and reciprocally 36 adjustable therewith, and scale graduations 37 and an indicator mark disposed between said 38 indicating member and said cutter supporting 39 member, substantially as and for the purpose 40 described.

41 2. In a device of the character described, 42 the combination with a head-stock and a cutter 43 supporting member rotatably mounted 44 therein, of an indicating member adjustably 45 mounted on said head-stock adjacent said 46 cutter supporting member, and reciprocally 47 adjustable therewith, scale graduations 48 and an indicator mark disposed between said 49 indicating member and said cutter supporting 50 member, and means for locking said indicating 51 member to said head-stock substantially 52 as and for the purpose described.

53 3. In a device of the character described, 54 the combination with a grinding wheel, a 55 table, a head-stock, and a cutter supporting 56 member rotatably mounted in said head- 57 stock, of an indicating member adjustably 58 mounted on said head-stock, and adjacent 59 said cutter supporting member and recip- 60 rocally adjustable therewith, scale gradu- 61 ations and an indicator mark disposed be- 62 tween said indicating member and said cutter 63 supporting member, and a tooth rest 64 whereby subsequent adjustments of said cutter 65 through said angle may be effected with- 66 out reference to said indicator and gradu- 67 ations, substantially as and for the purpose 68 described.

HERMAN R. ISLER.
